[57] CLAIM

The ornamental design for a copying machine with
document handler and sorter, substantially as shown
and described.

DESCRIPTION

FIG. 1 is a front and top-right perspective view of a
copying machine with document handler and sorter
showing our new design;

FIG. 2 is a front and top-left perspective view thereof;

FIG. 3 is a top-front perspective view thereof;

FIG. 4 is a rear elevational view thereof.

The bottom, not shown, is flat, plain and unornamented.

FIG. 1

FIG. 2

FIG. 3

FIG. 4
